UNITED STATES PATENT OFFICE.

ALBERT W. ADIX AND GEORGE W. HAGLUND, OF BOONE, IOWA.

FOLDABLE CRATE OR BOX.

1,315,175.

Specification of Letters Patent.

Patented Sept. 2, 1919.

Application filed February 27, 1919. Serial No. 279,598.

To all whom it may concern:

Be it known that we, ALBERT W. ADIX and GEORGE W. HAGLUND, citizens of the United States, residing at Boone, in the 5 county of Boone and State of Iowa, have invented certain new and useful Improvements in Foldable Crates or Boxes, of which the following is a specification.

This invention relates to improvements in 10 foldable crates or boxes, adapted for shipping hogs, sheep, or the like.

An important object of the invention is to provide a crate of the above mentioned character, all parts of which are permanently secured together and may be folded or collapsed in an expeditious and convenient manner.

A further object of the invention is to provide a crate of the above mentioned 20 character which is simple in construction, inexpensive to manufacture, strong and durable.

Other objects and advantages of the invention will be apparent during the course 25 of the following description.

In the accompanying drawings forming a part of this specification, and in which like numerals are employed to designate like parts throughout the same:

30 Figure 1 is a side elevation of a crate or box embodying our invention;

Fig. 2 is a plan view of the same;

Fig. 3 is a longitudinal horizontal sectional view, taken on the line 3—3 of 35 Fig. 1;

Fig. 4 is a vertical longitudinal sectional view through the crate, with one end-member open and the other closed;

Fig. 5 is an end elevation of the crate or 40 box;

Fig. 6 is a transverse sectional view, taken on the line 6—6 of Fig. 1;

Fig. 7 is an end elevation of the device collapsed; and

45 Fig. 8 is a plan view of the same collapsed.

In the drawings, wherein for the purpose of illustration is shown a preferred embodiment of our invention, the numeral 10 designates side-members of the crate or box, 50 each of which is preferably formed of vertical corner strips or bars 11, connected by spaced horizontal strips 12, affording open-

ings therebetween for the purpose of ventilation.

The numerals 13 and 14 designate a top member and a bottom member, respectively. The top member is formed in longitudinal top sections 15, each of which embody transverse strips 16 rigidly connected by longitudinal strips 17 spaced for the purpose of 55 ventilation. The longitudinal top sections are permanently hinged together, as shown at 18, and are adapted to fold inwardly. These top sections are also hinged to the side member 10, by hinges 19, secured to the 60 transverse strips 16, at points disposed near and spaced from their outer ends, and these hinges are secured to the transverse bars or strips 11 of the side members. The transverse strips 16 project laterally and outwardly beyond the longitudinal strips 17, for a substantial distance and overlap the upper ends of the transverse strips 11, for forming a knee-joint therewith, which will permit the top sections to swing inwardly 65 to fold but positively preventing them from swinging outwardly beyond a horizontal position.

Pivoted to the strip 17 of one top section 70 15, as shown at 20, is a lock bar 21, adapted to be shifted to a transverse position to project beyond the top sections and engage with and above the uppermost longitudinal strips 12 of the side members. This lock bar serves as means to lock the top sections 75 in the upper or standard position.

The bottom 14 is also formed in longitudinal bottom-sections 22, having transverse bars 23 rigidly secured to the exterior thereof. These transverse bars project beyond the bottom sections 22 for a substantial distance and are adapted to overlap and contact with the lower ends of the side members as shown. The bottom sections 22 are connected by means of hinges 24 and 80 are therefore adapted to swing inwardly or upwardly to fold. These bottom-sections are also connected with the side members, by hinges 25 secured thereto and to the transverse strips 11 of the side members 10. Particular attention is called to the fact 85 that the bottom-sections 22 are arranged within the side members and are adapted to fold upwardly into or between the same,

while the top sections are arranged exteriorly thereof and are adapted to fold downwardly into or between the same.

5 The numeral 26 designates a lock bar pivoted to one bottom-section, as shown at 27. This lock bar is arranged exterior of the bottom-sections and projects beyond the same for substantial distances to engage with the bottoms of the side members, the 10 same contacting with stop brackets 28.

15 The numeral 29 designates end members, each of which is formed of inner vertical strips or bars 30, connected by horizontal spaced strips or bars 31. The vertical strips are adapted for insertion within or between the top sections and the bottom sections, and preferably slidably contact therewith. The outer or horizontal strips 31 project beyond the strips 30 and preferably substantially 20 flush with the longitudinal strips 12 of the side members. Each end member is hinged to one side member, by hinges 32, which are secured to the exterior surfaces of the top and bottom horizontal strips 31 and to the 25 top and bottom strips 12. These end members are therefore adapted to be folded outwardly to lie substantially flat upon the side member, as clearly illustrated in Fig. 8. Each end member may be held in the closed 30 position by any suitable means and we have shown a hasp 33 secured thereto adapted to receive a staple 34, secured to the side member, such staple receiving a hook 35 or other lock device.

35 When the crate is assembled and it is desired to collapse the same, the end members 29 may first be swung to the folded position, in contact with the outer side of the side member 10. When this is done, the lock 40 bars 21 and 26 may be swung to the inactive position and the top sections and the bottom sections may then be folded inwardly. This folded arrangement is clearly shown in Fig. 7, which is an end elevation of the folded 45 crate.

It is to be understood that the form of our invention herewith shown and described is to be taken as a preferred example of the 50 same, and that various changes in the shape, size, and arrangement of parts may be resorted to without departing from the spirit of the invention or the scope of the subjoined claims.

Having thus described our invention, we 55 claim:—

1. In a crate or box of the character described, a pair of side-members, a top member including longitudinal top sections having their inner edges hinged together and 60 their outer edges hinged to the side-members, a bar pivotally connected to one of said top sections and adapted to be shifted to a transverse position, so that its ends project

beyond the top section and engage the side members, a bottom member including bottom sections having their inner edges hinged together and their outer edges hinged to the side-members, end-members hinged to one side member and having portions adapted to be moved to a position between the 70 top and bottom members, and means for maintaining the end-members in the closed position.

2. In a crate or box of the character described, a pair of side-members, a top-member including longitudinal top sections having their inner edges hinged together and their outer edges hinged to the side-members so that they are adapted to fold downwardly and inwardly between the side-members, means for holding said top sections in elevated position, a bottom-member including longitudinal bottom sections having their inner edges hinged together and their outer edges hinged to the side-members so 85 that they are adapted to be folded inwardly to assume a position between the side-members, end-members hinged to one side-member and adapted to be swung outwardly for assuming a folded position upon the exterior 90 of this side member, and means for holding the end-members in the closed position.

3. In a crate or box of the character described, a pair of side-members, a top-member including longitudinal top sections, each 95 top section having transverse strips, hinges secured to the inner sides of the transverse strips and arranged at points disposed inwardly of and spaced a substantial distance from the outer ends of the strips, means 100 for securing the hinges to the inner side of the side-member so that the transverse strips have their outer ends projecting over and across portions of the end-member, said hinges thereby forming a knee-joint so that 105 each longitudinal top section may be swung inwardly between the side members but cannot be swung upwardly beyond a substantially horizontal position, a bottom-member including bottom sections, each bottom section having transverse strips secured to the 110 lower portion thereof and extending outwardly beyond the same to overlap a portion of the side-member, hinges connecting the outer edge of the bottom section and the 115 end-member and forming with the last named transverse strips a knee-joint so that the bottom sections may be swung upwardly and inwardly and cannot be swung downwardly beyond a substantially horizontal 120 position, means for holding the top and bottom-members in the open position, and end-members to engage with the side members.

4. In a crate or box of the character described, side-members, a top-member including longitudinal top sections which have 125

their inner edges hinged together and their outer edges hinged to the side members so that the top sections may be folded inwardly between the side members, and a lock 5 bar pivoted to one top section and adapted to be shifted to a transverse position so that its ends project beyond the top section and contact with the side members.

In testimony whereof we affix our signatures in presence of two witnesses.

ALBERT W. ADIX.
GEORGE W. HAGLUND.
